Inventor

Ernest W. Marshall

UNITED STATES PATENT OFFICE.

ERNEST W. MARSHALL, OF YONKERS, NEW YORK.

ELEVATOR-SIGNAL REFLECTOR.

Application filed December 6, 1919. Serial No. 342,971.

To all whom it may concern:

Be it known that I, ERNEST W. MARSHALL, a citizen of the United States, and a resident of Yonkers, Westchester County, and ⁵ State of New York, United States of America, have invented certain new and useful Improvements in Elevator-Signal Reflectors, of which the following is a specification, reference being had to the accompanying drawings, forming a part thereof.

This invention relates to a new and useful device to be used in conjunction with elevator signals, and its object is to provide a reflector by means of which spaced signals ¹⁵ may be seen from a desired point. More specifically, its object is to provide a curved reflector by means of which the signals may be seen from different positions in relation to that of the reflector.

²⁰ These and other objects of the invention will appear in the following specification in which I will describe my invention and the novel features of which will be set forth in appended claims.

²⁵ Referring to the drawings:

Figure 1 is an elevation of the enclosure of an elevator hatchway at a single floor for a bank of elevators for each of which a door is provided with the light signals for each ³⁰ elevator and with a reflector which is made in accordance with and embodies this invention.

Figure 2 is a front elevation, and

Figure 3 a sectional side elevation of one ³⁵ embodiment of the invention.

Figures 4 and 5 are corresponding views of another form of construction.

Figures 6 and 7 are corresponding views of a still further modified form of construction.

Figure 8 is a side elevation of a spherical reflector which is also constructed for the purpose of making use of this invention.

Figure 9 is a front elevation, and

Figure 10 a side view of an elevator signal push button box with one of the improved reflectors thereon.

Figure 11 is a diagrammatic plan view of a plurality of elevator signals which are not

in a single line showing how one of these reflectors may be used under such conditions.

Like characters of reference designate corresponding parts in all the figures of the drawings.

10 designates the enclosure for a bank of ⁵⁵ four elevators with doors above each of which is a pair of light signals 11 and 12. At 13 is a push button switch comprising an up signal button 14 and a down signal button 15. In signal systems in common ⁶⁰ use, the arrangements are such that after an up push button, such as 14, has been pressed, a car approaching the floor from below at which the button is located will cause its respective up signal light 11 to be illuminated, and after a down push button 15 has been ⁶⁵ pressed, a car approaching such a floor from above, will cause its respective down signal light 12 to be illuminated. It is generally difficult especially where there are many ⁷⁰ elevators, and sometimes impossible for the one who pushed the button to watch all of the light signals, or even to stand in a position from which all of them are visible. This results not only in inconvenience to ⁷⁵ the users of the elevators, but in a considerable delay in the elevator service.

According to this invention, a reflector is placed near the push buttons or in some other convenient position which has its reflecting surface so formed that any or all of the signal lights will be seen thereon from any position relative to the reflector.

A simple form of such reflector is shown in Figures 1, 2 and 3, and designated by the ⁸⁵ reference numeral 20. This comprises a bracket having a back 21 with a rim 22 extending at an angle therefrom and a convexly curved reflector 23 supported thereby and secured in place by a screw 24. As ⁹⁰ shown the back has a portion which extends beyond the reflector with the words "Elevator Signal Reflector" thereon.

Before specifically describing the structures in the other figures of the drawings, I ⁹⁵ will point out the manner in which this device operates. Assume that a passenger has pressed the push button 15 and that one or

more cars are approaching the floor from above. Shortly before the first of these cars arrives at the floor at which the button has been pressed, its down signal light 12 will 5 be illuminated. Because of the curved surface of the reflector 23, the person standing near the push button may see this light reflected thereon no matter whether he is standing directly in front of the push button or to the right or to the left thereof. The 10 particular point on the reflector at which the light will appear will depend upon the position at which the person is standing. Consequently, regardless of the position at 15 which the person is standing relative to the reflector, he may by directing his eyes towards the reflector, see any or all of the signal lights which may be illuminated without the inconvenience of moving his eyes 20 back and forth across a plurality of such signals and without the inconvenience of moving to one end of the line of signals to a position where he may be able to see all of them at once. The result is that the person 25 who has pushed the button is able to tell easily which of the cars is to be ready for him to enter in ample time to move to the door of such car and to be ready to enter the car immediately after the door is opened by 30 the car operator. Thus the period of stop of the car at the floor is minimized and the elevator service speeded up to that extent.

The device shown in Figure 8 comprises a back 30 which may be fastened in a desired place. This supports a spherical mirror 31, the curved surface of which will reflect the signal lights in the manner previously described.

It is not necessary that the reflecting surface be convex and in Figure 4 a construction is shown which comprises a back 40 with a rim 41 extending at an angle therefrom and supporting a concavely curved reflector 42 which is secured in place by a 45 screw 43. This works in a manner somewhat like that described in connection with the device illustrated in the first three figures of the drawings with the exception of that when a light is illuminated to the left of the observer, the reflection thereof will appear at the right hand side of the reflector.

Instead of a uniformly curved surface the reflector may, of course, be made of a plurality of flat facets disposed on a curve in 55 order to produce the desired result. The reflectors shown in Figure 1-5 are curved in two planes but this is not necessary in order to produce the desired result. For example, the structure shown in Figures 6 and 7 comprises a housing 50 which supports a reflector 51 which is curved in only one direction. This is true also of the reflector shown in Figures 9 and 10 which is designated by the reference numeral 60. In the latter 65 case, this is either an integral part of the

push button box 13 or is a member affixed thereto in the position shown.

In Figure 11 a plurality of light signals 16 are shown in alinement with each other with other light signals 17 in another line. In 70 this case, a curved reflector is placed at 70 on which the signal lights are visible to the person standing either in front of one or the other of the rows of light signals 16 or 17. In this connection it may be pointed 75 out that when elevators are placed on opposite sides of a hall and facing each other, a person may see the signal light from any one of them on one of these reflectors without changing his position provided the reflector is placed at a sufficient height to prevent the person coming between the signal light and the reflector.

This invention is obviously capable of being embodied in structures of many different kinds, and I have illustrated and described a number of constructions for the purpose of showing that I do not intend to be limited to any specific form or construction. In 80 fact, I intend no limitations other than those 90 imposed by the appended claims.

What I claim is:

1. A signal reflector adapted to be used in conjunction with a plurality of spaced visible signals, having a reflecting surface 95 so curved as to reflect each of the signals in such a manner that it may be seen from a plurality of different positions, and means for securing said signal reflector in a fixed position relative to the signals. 100

2. In combination with a plurality of spaced visible signals, a signal reflector placed in a fixed position relative to the signals, and having a reflecting surface so curved as to reflect each of the signals in 105 such a manner that it may be seen from a plurality of different positions.

3. An elevator signal system comprising a plurality of spaced visible signals, a control box for the signals placed in a fixed 110 position relative to the signals, and a reflecting surface so curved as to reflect each of the signals in such a manner that it may be seen from a plurality of different positions. 115

4. The combination with a bank of elevators provided with individual visible signals, of a signal reflector having a reflecting surface so curved as to reflect each of the signals in such a manner that it may be seen from a plurality of different positions, to thereby enable the operation of the different signals to be observed from different positions in respect of the signals and the reflector. 120

5. A signal reflector adapted to be used in conjunction with a plurality of spaced visible signals, having a reflector with different parts thereof standing in different angular relations so as to reflect each of 130

the signals in such a manner that it may be seen from a plurality of different positions, and means for securing said signal reflector in a fixed position relative to the signals.

6. An elevator signal system comprising a plurality of spaced visible signals, a control box for the signals placed in a fixed position relative to the signals, and a re-

flector with different parts thereof standing in different angular relations so as to reflect each of the signals in such a manner that it may be seen from a plurality of different positions.

In witness whereof, I hereunto set my hand this 5th day of December, 1919.

ERNEST W. MARSHALL.
